SEMAUTOMATIC RIFLE

Edgar D. Martin and George E. Martin,
Corning, Ohio

Application April 30, 1948, Serial No. 24,304

6 Claims. (Cl. 89—139)

1

This invention relates to firearms and more particularly to that class of firearms wherein the recoil force is employed to eject an expended cartridge and to perform additional functions whereby operation of the firearm is semi-automatic.

A main object of the invention is to provide a novel and improved firearm of the semi-automatic type which is very safe to handle, sturdy in construction, and not subject to jamming.

A further object of the invention is to provide an improved semi-automatic firearm wherein a succession of cartridges may be fired without requiring the retraction of the bolt for each cartridge, the bolt being automatically moved rearwardly after the firing of a cartridge by recoil action, the firearm including safety means for preventing accidental firing thereof, and being very reliable in operation.

Further objects and advantages of the invention will become apparent from the following description and claims, and from the accompanying drawings, wherein:

Figure 1 is a longitudinal vertical cross-sectional view taken through the breech portion of a semi-automatic rifle constructed in accordance with the present invention, the rifle being shown in a cocked position.

Figure 2 is a view similar to Figure 1 but showing the rifle parts in firing positions, the locking means for the cartridge clip being shown in a released position.

Figure 3 is a longitudinal horizontal cross-sectional view taken through the breech portion of the rifle of Figure 1.

Figure 4 is a vertical transverse cross-sectional view taken on line 4—4 of Figure 1.

Figure 5 is a vertical transverse cross-sectional view taken on line 5—5 of Figure 1.

Figure 6 is a vertical cross-sectional view taken on line 6—6 of Figure 1.

Figure 7 is a vertical cross-sectional view taken on line 7—7 of Figure 1.

Figure 8 is a fragmentary side elevational view of the rifle of Figure 1.

Figure 9 is a transverse cross-sectional detail view taken through the bolt of the rifle of Figure 1 on line 9—9 of Figure 10.

Figure 10 is an enlarged perspective detail view of the bolt of the rifle of Figure 1.

Figure 11 is an enlarged fragmentary detail horizontal cross-sectional view taken through the receiver of the rifle of Figure 1 adjacent the forward end of the bolt, showing how an expend-

ed cartridge is ejected from the rifle by recoil action.

Referring to the drawings, 11 designates the barrel of the rifle, the rifle stock being shown at 12. Designated at 13 is the receiver, the rear end of barrel 11 being threaded into the forward end of the receiver. Rigidly secured to and depending from the forward portion of receiver 12 is the magazine housing 14 and likewise rigidly secured to and depending from the rear portion of receiver 12 is the sear and trigger housing 15. The stock 12 is suitably recessed at 16 to receive the depending housings 14 and 15. Housing 15 is formed with a bottom transverse bar element 17. Secured to bar element 17 by a machine screw 18 is the forward end of the trigger guard 19. The rear end of said trigger guard is secured to the underside of stock 12 by a screw 20. The magazine housing 14 is secured to stock 12 by suitable fastening means, not shown.

Pivottally secured on pin 21 in the forward portion of sear housing 15 is the sear block 22, said block being biased downwardly by a spring 23 acting upwardly on a pin member 24 bearing on the bottom of receiver 13. Designated at 25 is the sear plate, said plate being formed with a slot 26 engaging the transverse pin 27. Designated at 28 is the sear spring which bears between pin 21 and the sear plate 25, biasing said plate rearwardly and upwardly with respect to pin 27. The top portion 29 of sear plate 25 projects through a slot 30 formed in receiver 13. The top portion 29 is forwardly and downwardly inclined and terminates at its forward end in a lug 31 adapted to overlie the top of sear block 22 when the rifle is in a cocked condition, as shown in Figure 1. The body portion of sear plate 25 is received in a vertical slot 32 formed in sear block 22.

The rear portion of sear block 22 is formed with a recess 33 in which is rotatably received the rounded end 34 of trigger arm 35. The trigger is generally designated at 35' and is pivoted to the side walls of housing 15 by a transverse pin 36. Trigger 35' is provided with a depending finger-actuated arm 37. When arm 37 is pulled rearwardly, sear block 22 is rotated downwardly around pin 21 by trigger arm 35. Pin 21 then acts on sear plate 25 to move the rear end of the top portion 29 of said sear plate downwardly. If thereafter there is no restraint on said rear end of top portion 29, spring 28 moves sear plate rearwardly and also rotates it upwardly with respect to pin 27, whereby lug 31 is moved down-

wardly into slot 32 into abutment with the front wall of said slot, as shown in Figure 2.

Designated at 38 is a safety catch which is rotatably mounted on a pin 39 secured between the side walls of housing 15, the catch having a spring pressed ball 38' mounted in the lower end thereof and which is movable into and out of seating engagement in a groove 38'' formed in the bottom bar element 17 of the housing 15 upon rotation of the catch 38 toward and away from the sear block 22. Safety catch 38 is formed with a notch 40 engageable with the rear end of sear block 22 when said catch is rotated from the full line position of Figure 1 to its dotted line position with the spring pressed ball 38' seating in the groove 38'' in the bottom bar element 17 of the housing 15, whereby block 22 is locked against downward rotation around pin 21. Catch 38 is provided with a laterally offset upwardly extending actuating arm 41 terminating in a knurled finger plate 42 positioned adjacent the rear portion of receiver 13. Block 22 is locked by moving plate 42 forwardly from the position shown in Figure 3.

Designated at 43 is a plug member which is threaded into the rear end of receiver 13. Plug member 43 is formed with an axial forwardly extending reduced sleeve element 44 and encircling said sleeve element is a strong coiled spring 45. Surrounding spring 45 and longitudinally slideable in receiver 13 is a generally cylindrical hammer member 46 whose bore is reduced at 47 to define an internal annular shoulder against which the forward end of spring 45 bears. The outer surface of hammer member 46 is flattened at its bottom forward portion as shown at 48, the shoulder at the rear end of said flattened portion being engageable by the rear end of sear plate top portion 29 to hold hammer member 46 in a cocked position, as shown in Figure 1, against the force of spring 45.

Designated at 49 is a bolt member slidably positioned in the forward portion of receiver 13. Bolt member 49 is generally cylindrical in external contour, as shown in Figures 9 and 10, and is formed with an intermediate transverse slot 50. Extending through said slot 50 and projecting through a longitudinal slot 51 formed in the side wall of receiver 13 is a finger bar 52 for manually retracting the bolt 49. Bolt 49 is formed with a longitudinal axial bore 53 at its rear portion in which is slidably positioned a headed pin 54, and encircling the shank of said pin is a spring 55 which extends into sleeve 44 and bears on the end wall of said sleeve at its rear end and on the head of pin 54 at its forward end. Bar 52 is formed with a recess 55' which receives the head of pin 54, thereby locking bar 52 to bolt 49. Spring 55 exerts a forward biasing pressure on said bolt through the pin 54 and bar 52.

Bolt 49 is formed with a longitudinal top groove 56 of rectangular cross-section and slidably fitting said groove 56 is a firing pin 57. The rear end of firing pin 57 is formed with a T-shaped head 58 which is received in a T-shaped recess formed in the forward end portion of hammer 46, whereby firing pin 57 is interlocked with hammer 46 for movement therewith.

The forward end of the groove in which firing pin 57 is supported on bolt 49 is increased in depth, as shown at 59. The forward end of firing pin 57 is formed with an enlarged head 61 adapted to engage the shoulder at the deepened

groove portion 59 when hammer 46 is in the cocked position shown in Figure 1.

Receiver 13 is formed adjacent its forward end with a longitudinal slot 62 in its side wall and with an internal rib 63 opposite slot 62. Rib 63 is formed with a forwardly facing shoulder 64, the shoulder 64 being adapted to engage the rim 65 of a cartridge case 66 when said cartridge case is driven rearwardly by recoil action when the rifle is fired. As shown in Figure 11, the cartridge case 66 is rotated, by impact with shoulder 64, and is kicked out of the receiver 13 through the slot 62. Bolt 49 is formed with a keyway 67 slidably receiving the rib 63. Pivotedly secured in the bolt 49 opposite said keyway is a forwardly extending hook member 68 biased counter-clockwise, as viewed in Figure 3, by a spring 69 positioned in a recess provided therefor in bolt 49 and bearing outwardly on the rear portion of hook member 68. The hooked end of member 68 is engaged over the rim 65 of the cartridge case 66 and provides a fulcrum for the pivotal movement of said cartridge case required to rotate it through slot 62, as illustrated in Figure 11.

Designated at 70 is a cartridge clip which is received in magazine housing 14 and contains a plurality of vertically stacked cartridges biased upwardly by a follower plate 71 and a follower spring 72 acting between plate 71 and the bottom wall of clip 70. The rear wall of the clip 70 is formed with an opening 73 and receivable therein is a lug 74 carried by a clip locking member 75. Member 75 is pivoted between the walls of magazine housing 14 at 76 and is biased toward a locking position by a spring 77 bearing between the bottom of receiver 13 and a bearing cup 78 formed in member 75. Spring 77 biases member 75 in a counter-clockwise direction, as viewed in Figure 1, whereby lug 74 is normally maintained in the opening 73 of a clip 70. The clip may be unlocked by manually rotating member 75 clockwise by means of a depending handle 78 carried by said member to the position shown in Figure 2. This is done whenever a clip is empty and is to be replaced by a new clip.

The forward end portion of bolt 49 is formed with a depending longitudinal rib 79 which normally overlies the top cartridge in clip 70, as shown in Figures 1 and 2. When the rifle is fired, the recoil moves bolt 49 rearwardly to eject the empty cartridge case, as above described and allows spring 72 to move the stacked cartridges upwardly so that the top cartridge in the stack moves into the position formerly occupied by the ejected cartridge case immediately prior to its ejection from receiver 13. When the bolt 49 is returned by spring 55 to the position of Figure 1, bolt 49 pushes the top cartridge into firing position in barrel 11.

In operating the rifle, the safety catch 38 is first moved to the released position shown in full line view in Figure 1. Finger bar 52 is then pulled back as far as it will go. This interlocks the upper rear end of sear plate 25 with the rear shoulder defined by flattened portion 48 of hammer member 46, latching the hammer member in cocked position. As bar member 52 is released, spring 55 moves bolt 49 forwardly and bolt 49 moves the top cartridge in clip 70 into firing position in barrel 11, as shown in Figure 1. Since the hammer spring 45 is relatively strong as compared to the sear spring 28, the lug 31 is held in overlying relation to the top of sear block 22. The rifle may now be fired by pulling on trigger arm 37, whereby sear plate 25 is piv-

oted downwardly, as above described, releasing the hammer 46 and causing the firing pin 57 to detonate the cartridge by the impact of its head 61 with the rim of the cartridge. Since the top rear portion of sear plate 25 is now unrestrained, sear spring 28 moves sear plate 25 into the position of Figure 2. Upon recoil, hammer 46 is driven rearwardly by bolt 49 and is again interlocked with the top rear end of sear plate 25, even if trigger arm 37 is held in its rearwardly pulled position. As above described, the recoil movement of bolt 49 and the empty cartridge case 66 causes said cartridge case to be ejected by rearward impact with shoulder 64, and as spring 55 returns bolt 49 forwardly a fresh cartridge is moved by said bolt into firing position in barrel 41. The rifle is now ready to be fired again.

The renewed interlock of sear plate top portion 29 with the hammer 46 returns the forward top lug 31 of the sear plate from the position of Figure 2, to the position of Figure 1 wherein it overlies the top surface of sear block 22.

When the rifle is loaded and cocked, if safety catch 38 is in its locked position, shown in dotted view in Figure 1, it is impossible to fire the rifle accidentally, inasmuch as both ends of the sear plate top portion abut the top surface of sear block 22, and said sear block is locked against rotation.

The isolation of hammer spring 45 from the bolt return spring 55 by sleeve member 44 makes jamming of said springs impossible.

While a specific embodiment of a firearm of the semi-automatic type has been disclosed in the foregoing description, it will be understood that various modifications within the spirit of the invention may occur to those skilled in the art. Therefore it is intended that no limitations be placed on the invention except as defined by the scope of the appended claims.

What is claimed is:

1. In a firearm of the character described, a receiver, a hammer member slidably mounted in said receiver, means biasing said hammer member forwardly, a forwardly facing shoulder carried on said hammer member, a sear housing secured to and depending from said receiver, a sear block pivotally mounted in said housing for rotation in a longitudinal plane, a trigger pivoted in said housing and interengaged with said sear block, a sear plate slidably and pivotally secured to said sear block, and spring means acting between said sear plate and sear block biasing said sear plate rearwardly and upwardly with respect to said sear block, the rear end of said sear plate being engageable with said shoulder.

2. In a firearm of the character described, a receiver, a hammer member slidably mounted in said receiver, means biasing said hammer member forwardly, a forwardly-facing shoulder carried on said hammer member, a sear block pivotally secured to said receiver, and a sear plate slidably and pivotally secured to said sear block and engageable with said shoulder.

3. In a firearm, a receiver, a hammer disposed within said receiver and slidably supported in the latter for movement from a cocked position into a firing position, spring means operatively connected to said hammer for biasing the latter into said firing position, a sear block mounted on said receiver for pivotal movement about a transverse axis toward and away from said receiver, a sear plate disposed contiguous to said sear block and

mounted on the latter for sliding movement longitudinally thereof and for pivotal movement about a second transverse axis spaced from said first transverse axis, said sear plate having its upper end extending through said receiver and engageable with said hammer in a select position of its sliding and rotary movement for locking said hammer in said cocked position, and trigger means operatively connected to said sear block for rotating the latter about said first transverse axis and for simultaneously effecting the sliding and pivotal movement of said sear plate out of said select position.

4. In a firearm, a receiver, a hammer disposed within said receiver and slidably supported in the latter for movement from a cocked position into a firing position, spring means operatively connected to said hammer for biasing the latter into said firing position, a sear block mounted on said receiver for pivotal movement about a transverse axis toward and away from said receiver, a sear plate disposed contiguous to said sear block and mounted on the latter for sliding movement longitudinally thereof and for pivotal movement about a second transverse axis spaced from said first transverse axis, said sear plate having its upper end extending through said receiver and engageable with said hammer in a select position of its sliding and rotary movement for locking said hammer in said cocked position, trigger means operatively connected to said sear block for rotating the latter about said first transverse axis and for simultaneously effecting the sliding and pivotal movement of said sear plate out of said select position, and resilient means operatively connected to said sear plate for biasing the latter into said select position.

5. In a firearm, a receiver, a hammer disposed within said receiver and slidably supported in the latter for movement from a cocked position into a firing position, spring means operatively connected to said hammer for biasing the latter into said firing position, a sear block mounted on said receiver for pivotal movement about a transverse axis toward and away from said receiver, a sear plate disposed contiguous to said sear block and mounted on the latter for sliding movement longitudinally thereof and for pivotal movement about a second transverse axis spaced from said first transverse axis, said sear plate having its upper end extending through said receiver and engageable with said hammer in a select position of its sliding and rotary movement for locking said hammer in said cocked position, trigger means operatively connected to said sear block for rotating the latter about said first transverse axis and for simultaneously effecting the sliding and pivotal movement of said sear plate out of said select position, and resilient means operatively connected to said sear plate for biasing the latter into said select position.

6. In a firearm, a receiver, a hammer disposed within said receiver and slidably supported in the latter for movement from a cocked position into a firing position, spring means operatively connected to said hammer for biasing the latter into said firing position, a sear block mounted on said receiver for pivotal movement about a transverse axis toward and away from said receiver, a sear plate disposed contiguous to said sear block and mounted on the latter for sliding movement longitudinally thereof and for pivotal movement about a second transverse axis spaced from said first transverse axis, said sear plate having its upper end extending through said receiver and

engageable with said hammer in a select position of its sliding and rotary movement for locking said hammer in said cocked position, trigger means operatively connected to said sear block for rotating the latter about said first transverse axis and for simultaneously effecting the sliding and pivotal movement of said sear plate out of said select position, resilient means operatively connected to said sear plate for biasing the latter into said select position, and another resilient means operatively connected to said sear block for biasing the latter away from said receiver.
